Primary Examiner — Kevin K. Rudzinski*Assistant Examiner* — Christina M. Dodson(74) *Attorney, Agent, or Firm* — Lavery, de Billy, L.L.P.; Gonzalo Lavin(57) **CLAIM**

The ornamental design for a solar tree light, as shown and described.

DESCRIPTION

FIG. 1 is a right front perspective view of a solar tree light showing my new design;

FIG. 2 is a top plan view thereof;

FIG. 3 is a front elevational view thereof;

FIG. 4 is a rear elevation elevational view thereof;

FIG. 5 is a right side elevational view thereof; and,

FIG. 6 is a left side elevational view thereof.
